UNITED STATES PATENT OFFICE.

HENRY W. GALBRAITH, OF AMARILLO, TEXAS.

INTERIOR BRACING OF SILOS.

1,151,871.

Specification of Letters Patent. Patented Aug. 31, 1915.

Application filed June 23, 1914. Serial No. 846,713.

To all whom it may concern:

Be it known that I, HENRY W. GALBRAITH, a citizen of the United States, residing at Amarillo, in the county of Potter and State of Texas, have invented certain new and useful Improvements in Interior Bracing of Silos, of which the following is a specification.

My invention relates to silos and more particularly to certain removable and replaceable devices for preventing the silos from collapsing when empty, and the object is to provide wooden stave silos with certain adjustable and economical braces which are easily and quickly applied, and which will be highly efficient in preventing the blowing down or collapsing of the silos when empty and which can be easily and quickly removed as the silos are being filled.

One object is to provide interior braces which will prevent the flattening of the sides of a circular silo.

Other objects and advantages will be fully explained in the following description and the invention will be more particularly pointed out in the claims.

Reference is had to the accompanying drawings which form a part of this application.

Figure 1 is a horizontal plan of a silo which is equipped with the improved braces. Fig. 2 is a horizontal section on an enlarged scale showing in detail one manner of adjusting the main circular brace. Fig. 3 is a broken vertical section taken along the line $\alpha-\alpha$ of Fig. 2. Fig. 4 is a broken vertical section showing one way of attaching the sectional braces to the main brace. Fig. 5 is a broken plan view, showing another way of attaching the sectional braces to the main brace. Fig. 6 is a broken vertical section showing one manner of mounting the main brace and the guy rods of cables. Fig. 7 is a broken vertical section, showing a variation in the main brace and the manner of mounting the same. Fig. 8 is a detail view, illustrating the manner of connecting the sectional braces when the interior circular brace is omitted. Fig. 9 is a plan view of the same. Fig. 10 is a variation from the devices shown in Figs. 8 and 9, showing also a portion of the silo wall in section and the manner of attaching the device thereto. Fig. 11 is a detail view illustrating a variation in the manner of connecting the ends of the interior circular brace. Fig. 12 illus-

trates a plate used on the U-bolts and which can be extended to form a band.

Similar characters of reference are used to indicate the same parts throughout the several views.

Sections of a silo are shown to illustrate the improvements applied to the silo. The silo is set on a base 1 and constructed of vertical wooden staves 2 which are usually joined by tongue and groove joints 3. The main brace 4 is a continuous brace which may be made of a single piece of L-shaped angle iron or as many pieces as may be desirable or convenient for adjusting the brace. The ends of the brace 4 may be connected by lapping the same as shown in Fig. 2 and bolting the same together. It is apparent that channel iron may be used instead of the L-shaped iron. The lapped portions of the angle iron are to be provided with a plurality of holes 5 so that the circle of the main brace may be varied to adapt the same to different sizes of the inner walls of silos. The ends of the brace 4 can be lapped on each other and the holes in the two ends can be made to register with each other so that the bolts 12 can be inserted to secure the ends together. The brace 4 can be mounted on the inner wall of the silo at as many points as may be necessary and the braces can be mounted as the ensilage is used or removed so that a person can stand on the ensilage and mount the brace and the brace can be removed as the silo is being filled. When ensilage is filled in up to a brace the brace can be removed and no ladders of any kind will be necessary. The brace 4 may be mounted with brackets 6, such as shown in Figs. 1 and 6, or with such devices as are shown in Fig. 7. The main brace 4 can be braced with a number of sectional or cross braces 7 and 8. Holes may be made in the base flange of the brace 4 so that the bent ends of the braces 7 and 8 can be inserted as shown in Fig. 4 or plates 9 may be attached to the base of brace 4 and the braces rods 7 and 8 are provided with turn buckles 7 and 8 caught in the plates 9. The brace 10 for adapting braces 7 and 8 to the brace 4. Guy wires or rods 11 may be caught in the attaching U-bolts 11' as shown in Fig. 6. It is apparent that the cross braces 7 and 8 may be constructed of any suitable material such as rods or cables.

The adjustment of the circular brace is made preferably only at the front of the

sil. The vertical flanges of the lapping portions of the brace 4 can be cut away and the ends lapped on each other and secured together by bolts 12. The ends of the 5 braces are made adjustable by providing a plurality of holes. The parts of the brace which lap on each other may be further braced against inward displacement by lugs 14, as shown in Figs. 2 and 3. The extreme 10 ends 15 of the brace 4 may extend along beside the flange 16 of the brace 4. One of the braces 4 can be permanently attached to the interior of the silo at the upper end because such braces do not interfere with the filling 15 of the silo. Below the upper end, the braces 4 are temporarily attached to the interior of the silo while empty. The brackets or clips 6 which hold the brace 4 are removed with the brace 4, and in order to retain the U- 20 bolts 17 in place, plates 18 are put in the place of the brackets 6 and secured on the ends of the U-bolts 17 by nuts 19. The form of the U-bolts 17 provides for holding the band or belt 20 and the guy wires 11 in place. The bands or belts 20 may be held in place by simple U-bolts 21, such as are shown in Fig. 7, and by plates 22, where there is no brace 4 to utilize the form of U- 25 bolts 17.

30 The sectional or cross braces 7 and 8 may be used without an interior brace such as 4 or 18 by providing U-bolts 23 and a bent plate 24 to engage the inner ends of the U-bolt 23. A ring 25 may be caught in the 35 bend of the plate 24 and sectional braces 7 and 8 caught in the ring 25. It is apparent from an inspection of Fig. 1 that these sectional braces will hold the silo in its normal condition and prevent the flattening of the 40 sides of the silo. The sectional braces 7 and 8 may also be connected to the sides of the silo by the form of U-bolts 26 shown in Fig. 10. A plate 27 may engage the ends of the U-bolts 26 to serve as washers for nuts 45 28. Instead of fastening the ends of the circular brace 4 together as heretofore described, the ends of the brace 4 may be made

to abut against each other and a binder 29 bolted to each of the abutting ends of the brace 4, as shown in Fig. 11.

50 It is apparent that various changes may be made without departing from my invention and there may be any suitable number of braces together with the cross braces which serve both as braces and tensioning 55 devices. The sectional braces 7 and 8 may be used independently of the circular braces herein described.

What I claim, is,

1. The combination with a silo of a removable inner rigid truss therefor comprising a brace member set on a transverse diameter of the silo, cordlike braces set on each side of said first mentioned brace and forming two triangles therewith, and means 60 whereby said braces may be placed under stress.

2. The combination with a silo of a rigid removable truss therefor comprising a pair of braces set substantially at right angles 70 and on diameters of the silo, said braces being substantially in the same plane, cordlike braces set on each side of each of said first mentioned braces and forming triangles therewith on both sides of the same, and means whereby said braces may be placed 75 under stress.

3. The combination with a silo and a guy therefor of a rigid removable truss arranged on the interior of the silo comprising a brace member set on a transverse diameter of the silo, one end of said brace member being connected to said guy, cordlike braces set on each side of said first mentioned brace and forming two triangles therewith, and 80 means whereby said braces may be placed under tension.

85 In testimony whereof, I set my hand in the presence of two witnesses, this 29th day of May, 1914.

HENRY W. GALBRAITH.
